UNITED STATES PATENT OFFICE.

THOMAS O'BRIEN, OF PHILADELPHIA, PENNSYLVANIA.

INSULATED JOINT FOR RAILROAD RAILS.

1,407,566.

Specification of Letters Patent. Patented Feb. 21, 1922.

Application filed July 26, 1921. Serial No. 487,668.

To all whom it may concern:

Be it known that I, THOMAS O'BRIEN, a citizen of the United States, residing in the city and county of Philadelphia, State of Pennsylvania, have invented a new and useful Insulated Joint for Railroad Rails, of which the following is a specification.

My invention consists of railroad rails having an insulated joint, and furthermore means for firmly connecting said rails and the cheek pieces employed with a chair, base or splice piece employed at said joint and aside of the latter, as will be hereinafter set forth.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a top or plan view of an insulated joint for railroad rails, and connecting means for the latter embodying my invention.

Figure 2 represents a vertical section thereof on line 2—2 Figure 1.

Figure 3 represents a vertical section thereof on line 3—3 Figure 1.

Figure 4 represents a perspective view of a portion of one of the cheek pieces employed.

Figure 5 represents a perspective view of an anchor member employed for connecting the cheek piece and rails with the chair or base member of the device.

Similar numerals of reference indicate corresponding parts in the figures. Referring to the drawings.

1 designates railroad rails, 2 designates cheek pieces on the sides thereof, and 3 designates a chair or base member on which the rail and cheek pieces are superimposed, said base member forming a splice piece for adjacent rails at the joint thereof.

4 designates bolts which are passed through the cheek pieces and the necks of the rails securing the cheek pieces with the rails, said bolts having thereon the tightening nuts 5 for evident purposes, said cheek pieces thus firmly connecting adjoining rails. On the under sides of the heads of the rails, the sides of the necks and around the bases of the rails is fibrous or other suitable material 55 6 which insulates the rails from the cheek pieces. Surrounding the bolts within the

openings in the cheek pieces are sleeves 7 of fibrous material which insulates the bolts from the cheek pieces.

Washers 8 are placed on the bolts in contact with the heads 9 of the bolts 4, and the nuts 5, and they are insulated therefrom by the discs 10 of fibrous or other material which encircle the sleeves 7 and have the washers connected with them, thus effectually insulating the contiguous parts of the device.

On the chair 3 is placed the pad 11 forming a cushion on which the bases of the rails are imposed on the meeting ends of said rails. The insulating material on the bases of the rails extends to and contact with said pad, as most plainly shown in Figure 2, thus insulating the rails from said pad and consequently from the base 3.

On one side of the chair 3 is the inturned flange 12 which is adapted to overhang the lower portion of the cheek piece 2 on said side and so interlockingly engage said cheek piece so as to hold it firmly in position 80 against the base of the rail and the neck thereof. The side of the chair opposite to the flange 12 is formed with the upright shoulder 13 which is so spaced as to readily allow the rail to be seated on the chair and the opposite cheek piece to be fitted under the flange 12 and held by the same as has been stated. Now, in order to lock the cheek

piece on the side adjacent to the shoulder 13, I employ the anchor 14 which consists of the 90 horizontal plate 15 and the vertical limb 16 depending from the outer side thereof, said plate 15 having therein the vertical bolt opening 17. Said plate 15 is imposed on the outer side of the adjacent cheek piece 2, 95 while the outer face of the limb 16 engages with the inner face of the shoulder 13, said faces being inclined or tapering so that said limb will wedge downwardly with said shoulder. Through the opening 17 and a 100

registering opening 18 in the base of the chair 3 is inserted the vertically extending bolt 19, the upper threaded end of which has thereon the nut 20 which when tightened presses the anchor firmly in place causing the 105 plate and limb of said anchor to hold the latter firmly against the side and lower portion of the cheek piece, and thus both cheek pieces are held tightly against the rails and the chair, and the rails are correspondingly 110 clamped to the chair whereby the rails are held steadily in place.

The flange 12 of the chair 3 which overhangs the adjacent cheek piece 2, as has been stated, has its underside inclined to accord with the inclined upper face of said cheek piece. Consequently, when the anchor 14 is drawn down by the bolt against the shoulder 13, the chair is moved in the present case to the right, whereby said flange 12 is moved over said cheek piece and wedged against the same and so the opposite sides of the rails are most firmly held in position by the cheek pieces and chair.

It will be seen that sufficient space exists between the shoulder 13 and the adjacent cheek piece to receive the anchor and the latter is located about the joint of adjacent rails at opposite sides thereof, and so the rails are most firmly sustained at said joint.

The cheek piece 2 shown in Figure 4 is provided with the recess 21 for the reception of the bolt 19, and both cheek pieces and the adjacent portions of the chair are formed with registering openings 22 for spiking purposes.

Having thus described my invention what

I claim as new and desire to secure by Letters Patent, is:—

1. In a railroad rail joint, cheek pieces, a chair having on one side an upright wedging shoulder and on the other side an inturned flange which latter is adapted to overhang the base of the adjacent cheek piece and to wedge thereagainst, a wedging anchor seated on the opposite cheek piece and having a vertical limb with an inclined face cooperating with the said wedging shoulder, and a bolt passed through said anchor and chair.

2. Railroad rails, cheek pieces, a chair, and an anchor, said chair having on one side a flange adapted to clamp one of said cheek pieces, and on the other side an upwardly extending shoulder, said anchor being adapted to clamp the other cheek piece and having its outer side provided with a member adapted to wedge with said shoulder.

THOMAS O'BRIEN.
